Primary Examiner — Abraham Bahta(74) *Attorney, Agent, or Firm* — Cohen & Grigsby, PC(57) **CLAIM**

The ornamental design for a rotatable magnetic calendar, as shown and described.

DESCRIPTION

FIG. 1 is a perspective view of the rotatable magnetic calendar.

FIG. 2 is a front view of the rotatable magnetic calendar.

FIG. 3 is a rear view of the rotatable magnetic calendar.

FIG. 4 is a left side view of the rotatable magnetic calendar.

FIG. 5 is a right side view of the rotatable magnetic calendar.

FIG. 6 is a top view of the rotatable magnetic calendar.

FIG. 7 is a bottom view of the rotatable magnetic calendar.

FIG. 8 is a detached perspective view of the rotatable magnetic calendar; and,

FIG. 9 is another detached perspective view of the rotatable magnetic calendar.
